UNITED STATES PATENT OFFICE.

FRANK D. POWELL, OF CHICAGO, ILLINOIS, ASSIGNOR TO ACME CARD SYSTEM COMPANY, OF CHICAGO, ILLINOIS, A CORPORATION OF ILLINOIS.

VISIBLE INDEX.

Application filed June 17, 1925. Serial No. 37,628.

This invention relates to improvements in visible indexes, and refers more particularly to improvements in visible card indexes adapted to hang in overlapping relation in 5 a frame.

One of the specific embodiments of the present invention resides in the construction of the supporting element for the cards. This supporting or hinge element takes the 10 form of a unitary structure having side plates connected by means of a flexible cross-connecting piece, the index cards being mountable on and removable from the side pieces.

The supporting or hinge element may itself 15 be utilized as a hanger or may be utilized in conjunction with a hanger on which it may be removably supported. The cards may be placed upon the side pieces by means of slots or notches either on or adjacent to the upper 20 side edges.

In the drawings, Fig. 1 is a fragmentary elevational view of an index frame to which my invention may be applied.

Fig. 2 is a cross-sectional view taken on 25 line 2—2 of Fig. 1. Fig. 3 is a perspective view of the hinge element. Fig. 4 is an enlarged fragmentary face view of one of the side plates. Fig. 5 is a cross-sectional view taken on line 5—5 of Fig. 3. Fig. 6 is a cross-sectional view taken on line 6—6 of Fig. 4. Fig. 7 is a cross-sectional view taken on line 30 7—7 of Fig. 4. Fig. 8 is an enlarged fragmentary face view of the right-hand upper edge of the card showing one form of slot. Fig. 9 is a view similar to Fig. 1, illustrating 35 the manner of mounting the index card having a slot projecting inwardly from its side edges.

Referring in detail to Figs. 1 to 8 both 40 inclusive of the drawings, 1 designates the central web, and 2 the flanged side channels of a metal supporting frame in substantial commercial use at the present time. Hangers 3 which may take the form of resilient lengths 45 of wire are extended across the body 1 of the frame and have spaced return-bent portions 4 for a purpose now to be explained.

Describing now some of the features of 50 the present invention, a hinge element such as designated as a whole 5 (Fig. 3) may comprise a pair of substantially flat side plates 6 having the upper rolled beaded edge 7, the latter forming pintle eyes. Each pair of side plates is formed into a unitary structure by 55 being connected by a cross-connecting piece 8

which in the present instance, is made of substantially flexible material such as clock spring metal and the like. Any method of attaching the plates 6 to the cross-connecting piece 8 may be utilized, such as the punched-out clinching members 9 on the plates 6.

Each plate is preferably provided with a pair of raised locking lips 10 (Fig. 4) which may be stamped out and raised from the face of the plate itself, as shown. These locking 65 lips 10 are adapted to register first with the enlarged openings 11 in the index cards 12, and subsequently with the smaller elongated slots 13 to lock same in place.

The arrangement is such that to mount a 70 card upon a pair of plates 6, it is only necessary to bend the card centrally, it being flexible enough to allow this, so that the enlarged notches 11 slip over the locking lips 10. The card is then flattened out, and the edges of 75 the locking lips overlie the portions of the slot 13, which is of reduced cross-section relative to the aperture 11.

By means of the present invention, it is 80 possible to mount the index cards in overlapping relation on a frame in which index cards are mountable on or removable from their supports without disturbing the set of the supports. In other words, in the constructions now on the market, each card is 85 provided with a pair of hinges placed on the upper edge of said card adjacent the side edges. These hinges are more or less permanently attached to the card, and in most cases this construction is preferable. However, it has been found necessary in certain instances to remove the hinges from the cards in order to allow the cards to be rolled around the platen of a typewriter, for instance.

The present invention was perfected to 95 allow ready removal of the cards from their hinge elements without removing the hinges from the hanger, or the hanger from the frame.

It is to be expressly understood that I may 100 dispense entirely with the hangers 3 and utilize what I have termed hinge elements, as the hangers or supporting elements for the cards on the frames. For instance, the ends of the cross-connecting piece 8 may be extended outwardly beyond the outer edges of 105 the plates 6, said projecting ends being placed between the channelled guides 2 of the frame. The inventive novelty of the present invention resides as heretofore pointed out, in the 110

case with which the cards are mountable on or removable from the hinge elements without disturbing the position of the hinge element relative to the frame.

5 In Fig. 9, there is shown a slightly modified form of construction in which the index cards instead of being provided with the ordinary slot as shown in Fig. 8 may be provided with a notch extending from the side edge inwardly as shown at 14. It is to be understood of course, that I do not wish to limit myself to the particular shape or position of the slots, as these slots may be formed on the side edges of the cards, or interior of the cards 10 as desired.

It is understood of course, that a plurality of cards are adapted to be mounted in overlapping relation in the frame spaced by means of the return-bent portions of the hangers.

20 The flexibility of the cross-connecting piece 8 allows the intermediate element 5 to be contracted centrally when being put in place or removed from position.

I claim as my invention:

25 1. A visible index, comprising in combination a supporting frame having side flanges, an index card, means for detachably supporting said index card on said frame, comprising a hanger adapted to have engagement with said frame in said side flanges, index card supporting elements adapted to have engagement with said hanger, comprising spaced hinge elements connected into a unitary structure by a connecting strip, said index card being mountable on or removable from said hinges without disturbing the position of the hinges relative to the hanger, or the hanger relative to the frame.

40 2. A visible index, comprising in combination a supporting frame having side flanges, an index card, means for detachably supporting said index card on said frame, comprising a hanger adapted to have engagement with said frame in said side flanges, index card supporting elements adapted to have engagement with said hanger, comprising spaced hinge elements connected into a unitary structure by a flexible connecting strip, said index card being mountable on or removable from said hinges without disturbing the position of the hinges relative to the hanger, or the hanger relative to the frame.

45 3. A visible index, comprising in combination a supporting frame having side flanges,

an index card, means for detachably supporting said index card on said frame, comprising a hanger adapted to have engagement with said frame in said side flanges, index card supporting elements adapted to have detachable engagement with said hanger, comprising spaced hinge elements connected into a unitary structure by a flexible connecting strip, said index card being mountable on or removable from said hinges without disturbing the position of the hinges relative to the hanger, or the hanger relative to the frame. 55

4. A visible index, comprising in combination a supporting frame having side flanges, an index card, means for detachably supporting said index card on said frame, comprising a hanger adapted to have detachable engagement with said frame in said side flanges, index card supporting elements adapted to have detachable engagement with said hanger, comprising spaced hinge elements 60 connected into a unitary structure by a flexible connecting strip, said index card being mountable on or removable from said hinges without disturbing the position of the hinges relative to the hanger, or the hanger relative to the frame. 70

5. In a visible index, in combination, a supporting frame having side flanges, a flexible hanger having return-bent ends, engaged by said side flanges, index card-supporting elements adapted to have detachable cooperative engagement with the return-bent ends of the hanger, comprising spaced hinges connected into a unitary structure by a flexible connecting strip, and an index card adapted 85 to be removably supported on said hinges. 90

6. A visible index, comprising in combination a supporting frame, an index card, means for detachably supporting said index card relative to said frame comprising a hanger 95 adapted to have cooperative engagement with said frame, index card supporting means adapted to cooperatively engage with said hanger, comprising spaced hinge elements connected into a unitary structure by a connecting strip, and means whereby said index card may be mounted on or removed from engagement with said hinge elements without disturbing the position of the hinge elements relative to the hanger or the hanger relative 100 to the frame. 105

FRANK D. POWELL.
